(57) **CLAIM**

The ornamental design for a fold up tool with center beam, as shown and described.

DESCRIPTION

FIG. 1 is a front elevational view showing my new design for a fold up tool with center beam;

FIG. 2 is a right side elevational view;

FIG. 3 is a bottom plan view;

FIG. 4 is a rear elevational view;

FIG. 5 is a left side elevational view;

FIG. 6 is a top plan view; and,

FIG. 7 is a front perspective view.
